Fig. 2. 10

Fig. 1.

Fig. 3.

The drawing shows a cross-sectional view of a mechanical component. It features a central vertical stem with a flared top section labeled 30. A horizontal rod or handle is attached to the side of the stem. The stem is supported by a housing with internal parts labeled 26, 27, 28, 29, 31, and 32. The housing has a flared base. The entire assembly is labeled 'fig. 1.' in a cursive script.

Attorney

UNITED STATES PATENT OFFICE.

ROBERT E. SCHIEBER, OF DETROIT, MICHIGAN.

FUEL-RESERVE DEVICE.

Application filed May 31, 1924. Serial No. 717,087.

To all whom it may concern:

Be it known that I, ROBERT E. SCHIEBER, a citizen of the United States of America, residing at Detroit, in the county of Wayne and State of Michigan, have invented certain new and useful Improvements in Fuel-Reserve Devices, of which the following is a specification, reference being had therein to the accompanying drawings.

This invention relates to that class of tanks or receptacles provided with atmospheric vents so that liquid may flow from a discharge opening. As an incident of such a tank I refer, hereinafter, to a gasoline fuel tank having a discharge opening, a filling opening, a cap or closure for the filling opening with said cap or closure provided with a vent. This type of fuel tank is commonly used in connection with automobiles.

The primary object of my invention is to furnish such a fuel tank with novel means for closing the atmospheric vent thereof, at a predetermined time, so that a reserve quantity of fuel will be temporarily retained in the tank, thus preventing the entire supply of fuel being used without a warning that such supply is about to be exhausted. This applies to motorists who often run out of fuel some distance from a fuel station and experience some trouble in reaching such station.

Another object of my invention is to provide a fuel-reserve device solely supported from the cap or closure of the fuel tank and my device with its cap can be readily substituted for the usual form of cap, consequently there is a large exploitation field in which my device may grow useful.

A further object of my invention is to provide a fuel-reserve device embodying a float-actuated normally open valve for the vent of a fuel tank, and associated with the float of the device is a tension device adapted to hold the valve closed against accidental unseating during the operation of an automobile having a fuel tank equipped with the device.

The above and other objects are attained by a construction that will be hereinafter described and then claimed, and reference will now be had to the drawing, wherein—

Figure 1 is a vertical sectional view of a portion of a fuel tank having a cap provided

with the fuel-reserve device, showing the valve of said device in its normally open position;

Fig. 2 is a similar view showing the valve in a closed position;

Fig. 3 is a vertical sectional view of a portion of a modified form of device, particularly the float thereof, and

Fig. 4 illustrates a modified form of valve that may form part of the device, and

Fig. 5 is a vertical sectional view of a further form of my invention.

In the drawing the reference numeral 1 denotes a tank having the bottom thereof provided with a discharge opening 2 for a quantity of gasoline or other fuel 3 within the tank. The fuel is placed in the tank through a filling opening 4 having an interiorly screwthreaded connection 5 for a cap 6 provided with a vent opening 7 and a finger or nut portion 8. The cap 6 may be of any well-known form having a vent opening and my device is adapted to be supported in its entirety by said cap.

My device comprises a valve rod 9 which, according to Figs. 1 and 2, normally extends through the vent opening 7 and has the upper end thereof provided with a valve 10 adapted to seat on the cap 6 and close the upper end of the vent, thus shutting off atmospheric communication for the tank. The valve 10 may be of spherical form so that it may be conveniently used as a knob or handle for manually raising the valve rod 9.

Suitably mounted on the lower end of the valve rod 9 and normally immersed in the quantity of fuel 3 is a float or buoyant body 11 that may conveniently be a piece of cork of cylindrical form. As the fuel flows from the tank and the level lowered, as shown in Fig. 1, the float 11 lowers or permits the valve 10 to close by gravity, shutting off communication with the atmosphere and preventing further flow of the fuel, consequently a quantity of the fuel will be held in reserve in the tank until the valve is opened. This may be manually accomplished to permit of enough fuel flowing to the carburetor of an internal combustion engine so that the engine may be operated to move an automobile to a fuel supply station. At such station the cap 6 is removed, carrying with it my device, and when the cap is

replaced the valve 10 is automatically raised by the float 11 being sustained by the fuel within the tank.

In order that my device may be of a substantial nature, I may inclose the float 11 by a two part cylindrical casing 12 apertured, as at 13 to permit of fuel entering a casing. The casing is supported by a tube 14 inclosing the valve rod 9 and the upper end of the tube 9 is fitted into the enlarged lower end of the vent 7, thus providing a rigid structure relative to the cap 6.

For fear that the vibrations of an automobile may prevent the valve 10 from sealing the vent 7 I prefer to use a tension device which is located within the casing 12 above the float 11. On the valve rod 9 I place a collar or support 15 for a cup member 16 supporting the coiled spring 17 encircling the valve rod 9 and bearing against the upper end of the casing 12. The tension of this spring is sufficient to hold the valve 10 firmly seated on the cap 6 when the float 11 is lowered, but the expansive force of said spring does not interfere with the float 11 maintaining the valve 10 open when said float is fully immersed in fuel.

As shown in Fig. 3 I may use a different type of spring 18; provide the casing 19 with a bottom opening 20 adapted to be closed by a valve 21 at the lower end of the float 22 on a valve rod 23, and this valve rod, according to Fig. 4, may have a conical valve 26 at its upper end adapted to close atmospheric ports 27 in an enlargement 28 forming part of the cap 29. The cap 29 may have a detachable apertured plug 30 to permit of the valve 26 being installed.

Reference will now be had to Fig. 5, showing a form of device wherein the casing 12 is off-set relative to the tube 14, and connected to said tube by a coupling member 31. The lower end of the valve rod 9 extends into the coupling member and is provided with a head 32 engaging the inner end 33 of a lever 34 pivoted in the lower slotted end of a coupling member 31. Encircling the valve rod 9, within the coupling member, is a coiled expansion spring 35 which holds the valve 10 normally seated. The lever 34 extends over the central portion of the float 11 and it is obvious that when the float is raised there will be a cam action at the head 32 which causes the valve 10 to be unseated and admit air to the tank 1. It will be noted that the tank 1 is supported by the coupling member 31 co-axially of the cap 6, so that the casing 12 may be moved through the filling opening 4 of the tank.

It is thought that the utility of my devices will be apparent without further description, and while in the drawing there are illustrated the preferred embodiments of my invention it is to be understood that the structural elements are susceptible to

such variations and modifications as fall within the scope of the appended claims.

What I claim is:—

1. In a fuel reserve device for a tank having a filling opening, a cap for the tank opening, said cap having an atmospheric vent so that fuel may flow from said tank, a float controlled valve carried by said cap adapted to seat on said cap by gravity to close said cap vent when a predetermined quantity of fuel is in said tank, and a tension device holding said valve seated on said cap.

2. In a fuel reserve device for a fuel tank having a discharge opening, a filling opening and a vent with the vent disposed to admit air to the tank so that fuel may flow from the discharge opening of said tank, a float controlled valve for the tank vent adapted to close the vent after a quantity of fuel flows from said tank, and a tension device associated with the float of said valve and adapted to hold said valve closed.

3. In a fuel reserve device for a tank having a filling opening, a cap for the tank opening, said cap having an atmospheric vent so that fuel may flow from said tank, a valve for the cap vent, an apertured casing supported from said cap, and means in said casing under the influence of fuel in said tank adapted to hold said valve normally open and cause said valve to close over the vent opening when fuel reaches a low predetermined level in said tank.

4. A fuel reserve device as called for in claim 3, wherein said means includes a float and a tension device with said device arranged to hold the valve to its seat.

5. A fuel tank having a discharge opening and a filling opening, a cap for the filling opening of the tank, said cap having a vent so that fuel may flow from the discharge opening of said tank, a tube carried by said cap and communicating with the vent thereof, an apertured casing carried by said tube, a rod in said tube extending into the cap vent and into said casing, a valve on said rod adapted to seat on said cap and close the vent thereof, and a float on said rod in said casing and buoyant in and on the fuel in the tank to hold said valve normally open and adapted to close said valve when the fuel in said tank reaches a predetermined level.

6. A fuel tank as called for in claim 5, and a spring in said casing adapted to prevent accidental unseating of the valve when seated on said cap.

In testimony whereof I affix my signature in presence of two witnesses.

ROBERT E. SCHIEBER.
